UNITED STATES PATENT OFFICE.

CHARLES M. HOLLINGSWORTH, OF WASHINGTON, DISTRICT OF COLUMBIA.

SHOE CLEANER AND POLISHER.

1,059,364.

Specification of Letters Patent. Patented Apr. 22, 1913.

Application filed April 21, 1910. Serial No. 556,689.

To all whom it may concern:

Be it known that I, CHARLES M. HOLLINGSWORTH, residing in the city of Washington, District of Columbia, have invented 5 certain new and useful Improvements in Shoe Cleaners and Polishers, of which the following is a specification.

My invention relates to certain new and useful improvements in shoe cleaners or polishers, and it primarily has for its object to provide a device of this character of a simple and effective construction which can be manufactured at a minimum expense and in which the wearing parts may be readily renewed. 15

More specifically my invention resides in supplying a convenient polishing implement for use when liquid polish is applied to shoes made of thin leather, such as vici kid; 20 and therefore to employ for the part which comes in rubbing or polishing contact with the leather, the surfaces of a soft and pliable material, such as cloth, which will not injure the leather and so arranged in folds 25 as to be durable and efficient.

Generally speaking, the invention resides in providing a holder which may be of any design or external configuration on its back. The holder is provided with a longitudinal 20 hole, preferably of circular form in cross section, while the operative face of the holder has a longitudinal slot that merges with the hole to form a channel in which the wiper is held. The wiper is also of a 35 peculiar construction, in virtue of which a more effective operation is possible.

In its more subordinate nature the invention also includes those novel details of construction, combination and arrangement of 40 parts all of which will be first fully described, then be specifically pointed out in the claims, and illustrated in the accompanying drawings, in which:—

Figure 1, is a perspective view showing 45 the use of my device. Fig. 2, is a perspective view of the device, the wiper or polisher being partly drawn out of the holder. Fig. 3, is a detail perspective view of the wiper showing how it is made up. Fig. 4, is a 50 cross section of the device. Fig. 5, is a view similar to Fig. 4 of a slightly modified construction. Fig. 6, is a detail perspective view of a further modified construction.

Referring now to the accompanying drawings 55 in which like letters and numerals of reference indicate like parts in all of the fig-

ures, 1 designates the holder which may be ornamented in any approved fashion, such ornamentation not being a part of my present invention is therefore not illustrated in 60 the drawings.

The holder 1 has a longitudinal bore 1^b which merges with a longitudinal slot 1^c at one face of the holder the slotted face 1^d of the holder being protected with resilient strips 2, as clearly indicated in Figs. 2 and 4 of the drawings. The ends of the holder 1 are round or curved as at 1^a for a purpose hereinafter to appear. 65

The wiper or polisher consists of a strip 70 3 which is lapped upon itself backward and forward, as shown in Fig. 3 of the drawings, and is then bent upon itself midway around a cord or other core member 4 to form the back or welt 3^a which is insertible into the bore 1^b so that the loops 3^b will project 75 through the slot 1^c, as shown in Figs. 1, 2, and 4 of the drawings. In folding the strip 3 into form the loops are gradually reduced from the first fold to the last, as shown in 80 Fig. 3 of the drawings, so that in practice when the implement is in use the parts will lie substantially in the position shown in Figs. 1, 2 and 4 of the drawings, whereby the flats or sides of the loops 3^b will lie or wipe 85 against the shoe S, see Fig. 4 instead of having the bend of the loop member 3^b to contact the shoe and perform the wiping function. After the wiper 3 has been folded, as shown in Fig. 3 of the drawings around the 90 core member 4 and folded further into position, as indicated in Figs. 2 and 4 of the drawings, the same is suitably stitched together as at 3^c whereby to hold the member 3 in a positoin to be readily inserted into the 95 slot 1^b.

By putting the holding member 4 within the back of the wiper the back 3^a of the wiper 3 will have sufficient elasticity or swell to fit tightly in the bore 1^b and thereby prevent longitudinal movement of the wiper 3 in the holder. 100

In practice the wiper 3 is made of a sufficiently greater length than the holder to project beyond the ends thereof so that when 105 the implement is used as shown in Fig. 1 of the drawings, the arch of the shoe or other incures thereof may be readily and conveniently reached by the user.

The strips 2 may or may not be used, as 110 desired, although I prefer to use the same as they lend greater resiliency to the wiper.

In practice the strips 2 and wiper 3 may be made either of felt, flannel or other suitable cloth of a resilient or semi-resilient nature. I prefer to make the wiper 3 of a cloth having a smooth surface, such as flannel and have that side of the cloth with the smooth surface exposed.

In Fig. 5 is shown a slight modification of the invention wherein the holder 1^x has two longitudinal bores 1^b and grooves 1^c and is also provided with the strips 2^x and an intermediate strip 2^y as shown, two wipers 3 being used in this form.

The construction shown in Fig. 6 is adapted for use in applying paste, polish or other substance to the shoe before it is rubbed up by the wiper or polisher 3. In this form of my invention the holder 1^x is bored as at 1^b and slotted as at 1^c to receive the wiper or applicator member 3^x, the construction of which is the same as that of the member 3 in the other forms of my invention.

It will be noticed that by folding the cloth member 3, as shown in Fig. 3 of the drawings, none of the edges of the cloth come into contact with the shoe but only the looped portions or folds 3^b thereof. By this construction the wiper 3 is rendered more elastic in its engagement with the shoe and a better polish may be brought up on the shoe than by the use of stiff brushes or by the use of polishing members in which the cut edge of the wiper or polisher parts are brought into direct contact with the shoe.

From the foregoing description taken in connection with the accompanying drawings, it is thought the complete construction operation and numerous advantages of my invention will be readily understood by those skilled in the art to which the invention appertains.

What I claim is:

1. An implement of the character described comprising a holder having a longitudinal channel in one face, a wiper held in said channel and consisting of a single strip folded back and forth upon itself to form loop portions, a core around which said folded strip is bent to form a back for said wiper, said wiper back being held in said channel.

2. An implement of the character described comprising a holder having a longitudinal channel in one face, a wiper consisting of a strip folded back upon itself to form loop portions, a core around which said folded strip is bent to form a back for said wiper, said wiper back being held in said channel.

3. An implement of the character described comprising a holder having a longitudinal channel in one face, a wiper held in said channel and consisting of a single strip folded back and forth upon itself to form loop portions, a core around which said

folded strip is bent to form a back for said wiper, said wiper back being held in said channel, said wiper being of a greater length than said holder to project beyond the ends of the same, said holder having curved ends around which said wiper ends may be bent when in use.

4. An implement of the character described comprising a holder having a longitudinal channel in one face, a wiper held in said channel and consisting of a single strip folded back and forth upon itself to form loop portions, a core around which said folded strip is bent to form a back for said wiper, said wiper back being held in said channel, and resilient strips secured to the channeled face of said holder at each side of said channel and over which some of said loop portions may lap.

5. An implement of the character described including a holder having a bore through its body, a slot merging with said bore and opening on the face of the holder, a soft pliable polishing member consisting of an engaging welt adapted to fit with retaining friction in the bore of the holder and having folds integral with said welt and projecting through said slot onto the face of the holder, said polishing member being of greater length than said bore and slot to project beyond the ends of the same, said holder having curved portions at the ends around which said polishing member ends may be bent when in use.

6. An implement of the character described comprising a holder having a longitudinal channel in one face, a wiper held in said channel and consisting of a single strip folded back and forth upon itself to form loop portions, a core around which said folded strip is bent to form a back for said wiper, said wiper back being held in said channel, said wiper being of a greater length than said holder to project beyond the ends of the same, said holder having curved ends around which said wiper ends may be bent, and resilient strips secured to the channeled face of said holder at each side of said channel and over which some of said loop portions may lap.

7. As an article of manufacture, a wiping and polishing member for polishing devices that comprises a strip of cloth folded back and forth upon itself to form loop portions, a resilient core around which said folded strip is bent, and means for securing said folded strip to retain said core.

8. As an article of manufacture, a wiping and polishing member for polishing devices that comprises a strip of cloth folded back and forth upon itself to form loop portions of successively decreasing length, a resilient core around which said folded strip is bent, and means for securing said folded strip to retain said core.

9. In a device of the character stated, a holding member having a bore through its body, a slot merging with said bore and opening on the face of the holder, in combination with the polishing member of a soft and pliable cloth-like body consisting essentially of an engaging welt adapted to fit with retaining friction in the bore of the

holder, said body having folds integral with said welt and projecting through said slots 16 onto the face of the holder.

CHARLES M. HOLLINGSWORTH.
